Patented Oct. 13, 1959

186,303

COMBINED BATHTUB AND SHOWER UNIT OR THE LIKE

Julian G. Everett, New York, N.Y., assignor to Crane
Co., Chicago, Ill., a corporation of Illinois

Application December 19, 1957, Serial No. 48,962

Term of patent 14 years

(Cl. D4—4)

Des. 186,303

PAGE 2

Fig. 3.

Fig. 4.

Fig. 1 is a perspective view of a combined bathtub and shower unit or the like embodying my new design;

Fig. 2 is a horizontal section thereof taken at a height somewhat above the forward curved rim portion;

Fig. 3 is a vertical section taken along line 3—3 of Fig. 2 in the direction of the arrows on a reduced scale; and

Fig. 4 is a vertical section taken along line 4—4 of Fig. 2 in the direction of the arrows, also on a reduced scale.

I claim:

The ornamental design for a combined bathtub and shower unit or the like, as shown.
